The ornamental design for a vehicle grille bezel, as shown and described.

DESCRIPTION

FIG. 1 is a perspective view of the vehicle grille bezel;
FIG. 2 is a front view thereof;
FIG. 3 is a left side perspective view thereof (where the right side view is omitted since the right side view is a mirror image of the left side view); and,
FIG. 4 is a top view thereof.
In the drawings, the portions shown by broken lines form no part of the claimed design.
